UNITED STATES PATENT OFFICE.

FRANK W. ADSIT, OF ST. PAUL, MINNESOTA, ASSIGNOR TO ADSIT GENERAL ELECTRIC COMPANY, OF MINNEAPOLIS, MINNESOTA, A CORPORATION OF MINNESOTA.

SELECTIVE LOCKOUT TELEPHONE SYSTEM.

1,214,638.

Specification of Letters Patent.

Patented Feb. 6, 1917.

Application filed June 30, 1914. Serial No. 848,161.

To all whom it may concern:

Be it known that I, FRANK W. ADSIT, a citizen of the United States, residing at St. Paul, in the county of Ramsey and State 5 of Minnesota, have invented certain new and useful Improvements in Selective Lock-out Telephone Systems, of which the following is a specification.

My invention relates to improvements in 10 selective lock out telephone systems.

In a system embodying my invention the stations of the respective subscribers on a party line are inter-communicating, and any one thereof may be called by any other 15 party without intervention of the central operator. Both as to ringing and as to telephonic communication, the operation of the system is selective, the instrument sets of the calling and called subscribers, only, being 20 effectively connected with the line as a result of a call. The central station may be signated in substantially the same way as any other station, and the central operator, of course, may effect calls by selective 25 calling apparatus associated with her cord circuit, and may put any two subscribers' lines into connection.

One of the objects of my invention is to provide a system wherein the party-initiated 30 calling operations may utilize alternating current, as of a ringing magneto, for the electrically controlled actions of securing the line, actuating the selectors, and ringing the called station; such arrangement enabling 35 the full power of the magneto to be utilized, giving positive and efficient actuation of the selectors, and dispensing with such commutators, rectifiers, or other adjuncts to the magneto as would be requisite 40 to enable any of these operations to be performed by direct or pulsating current.

Another object of my invention is to provide a system wherein the releasing functions incident to clearing a line and restoring 45 the selector appliances at the subscribers' stations to normal condition may be effected by current of a different character, as direct current, preferably derived from a central battery, and, further, effectively 50 to control the release current supply that the line may be automatically cleared upon the termination of an inter-communicati-

cating call or may arbitrarily be cleared at the will of the central operator.

A further object of my invention is to 55 provide for automatic timing of the automatic clearing-out or release operations so as to fix the permitted durations of a ringing interval and of a communication interval, in order that rules of the line as to 60 maximum time allotted for endeavoring to secure a party who fails to answer, and for a single use of the line for conversation, may automatically be enforced; and further to make such automatic release operations sub- 65 ject to suspension by means within the control of the central operator.

Other objects of my invention are to insure that the communicating parties will automatically be notified, shortly before the 70 expiration of the maximum allotted time for communication, that their time is almost up; to insure the proper setting and releasing of the central station line signals under all conditions where the attention of 75 the operator is necessary to supplement or to supersede the automatic operations of the system; and to provide effective central control of all normally automatic operations.

Another object of my invention is to provide 80 the selective mechanism in such structural and systemic relation to the ordinary telephone equipment of a party line that the subscriber's station selective apparatus for the practice of my invention may 85 readily be added as an attachment to the already present telephone sets; and so to provide such central station equipment that minimum alterations may be necessary 90 properly to equip a central switchboard for most effective employment as part of my system.

Other objects of my invention are to provide, in simple, cheap, economical and efficient form and systemic relation, suitable 95 appliances for effectively attaining the advantageous results herein described.

In the accompanying drawings I have shown, and will describe, a single systemic embodiment of my invention for purposes 100 of full disclosure thereof, but it will be understood by those skilled in the art that many changes, variations, and modifications may be made in the structure and arrange-

ment of the parts without departure from the spirit of my invention and within the scope of the appended claims.

In the drawings Figure 1 shows, under normal conditions, the apparatus of two subscribers' stations on a party line; Fig. 2 shows a central station equipment appurtenant to a line; Fig. 3 shows some features of a suitable cord circuit arrangement for the central operator; Fig. 4 shows diagrammatically certain circuit connections existing during the selecting operation for an intercommunicating call; Fig. 5 indicates diagrammatically conditions during the ringing operation; Fig. 6 indicates certain circuit conditions existing during an interval of telephonic communication between the intercommunicating parties; impending release; Fig. 7 indicates certain circuit conditions incident to releasing operation; Fig. 8 shows a central-energy installation.

I.

Particularly to describe the construction illustrated in the diagrammatic drawings, A¹, A², A³ represent subscribers' stations (of which there will often be, say, from 10 to 15, in practice) connected with the line wires 10 and 11 of a metallic or two-wire party line; B indicates in general central-station automatic apparatus appurtenant to that line; C indicates in general the manually-controlled switch-board equipment including the line jack and its associated keys that are appurtenant to said line; and D represents a cord circuit apparatus.

II. General plan, operations at subscriber's station.

At each subscriber's station there is a suitable instrument set, a¹, an alternating current generator, such as the customary hand-operated magneto a², normally short circuited, when not in operation, a manually operable selector-setter a³; an automatic step-up alternating-current-responsive selector a⁴; automatic circuit controlling devices a⁵, which in this particular embodiment includes two relays having switch-sets a⁷ and a⁸ and release means a⁶ for the automatic devices. The alternating current magneto supplies current for all of the selective operations. To make a call the party sets the call by turning the selector-setter to the desired number and turns the magneto crank, continuing its operation until the bell at his own station has rung and stopped, its cessation showing that the called party has answered. The selectors a⁴ at all stations on the line work synchronously in response to alternating impulses in the line, and the entire selective operation, initiated from a calling station to signal either "central" or any other party on the party line, is effected by agencies receiving alternating current

from the magneto at the calling station. The selector-setter a³ at the calling station, coöperating with suitable of the automatic circuit controlling devices a⁵ at that station, predetermines the number of alternating impulses that will be transmitted via the metallic line circuit to the several selectors; and, at all other stations than that calling, the selector-response disables or locks out their magnetos to prevent conflicting calls. The selector response to any call-setting of the setter a³ effects operative connection of the called station instrument-set with the line, for ringing and talking purposes, and locks out all other stations. The automatic circuit controlling devices a⁵, upon causing cessation of the selector-actuating impulses, shift the magneto connections to connect it in ground-return ringing circuit with the bells at the calling and selectively-called stations and condition the instrument-set at the calling station for functional coöperation with the line, so that when the switch hooks at the two stations are raised the two parties are in communication; no other party having been signaled, and no other party (save central) having it within his power to "listen in" on the line. The apparatus at each subscriber's station has its release means a⁶, for restoring normal conditions, preferably operable in response to direct current supplied from the central station, but the direct-current supply means at central is normally subject to automatic control from the switch hooks of the subscribers, so that release may take place when a party "hangs up."

All of the apparatus at a subscriber's station, other than the conventional instrument set and magneto, may be made small enough to be housed in a box a¹⁰ (see station A³) so that the apparatus may be installed on the wall board of, or otherwise located contiguous to, the usual instrument set.

III. General plan; operations of central apparatus on the line.

III^a. At the central station there is, in the equipment B local to the line, preferably a timer apparatus, b¹, automatically potentiated in response to the alternating current line impulses; direct-current-responsive release means b² for restoring all automatically moved timer and central parts to normal position; and for connecting a central current source of supply, b³, with the line to energize the release devices at the subscribers' stations; and release-actuating means, the latter being preferably subject to multiple control so that there will be an automatic release under various predetermined conditions such as a party's failing to answer or hanging up, or upon lapse of a maximum time limit, and so that the central operator may, through appropriate instru-

5 mentalities of switch-board set C, clear the line at any time or disable the automatic release devices at will. These instrumentalities are supplemented with a signal responsive selector a^3 controlling the line lamp or other signal device that attracts the attention of "central."

10 III^b. The automatic devices at central so operate that selective signal transmission in the line effects a potentiation of the timer b^1 . The consequent operation of the timer allots a predetermined time to the ringing operation on the line; then, after lapse of the ringing time, potentiates the release-
15 actuating devices to respond functionally to such grounding of the line as is caused by a party's "hanging up" or failing to answer; then, after lapse of a further time, predetermined according to rules of the company, 20 automatically occasions the operation of the release devices at central station and causes the battery to be bridged across the line to restore all subscriber's appliances to normal and "clear out" the whole line. The automatic clearing-out apparatus works, therefore, either upon failure of the called party to answer or arbitrarily at the end of the allotted talking time, or immediately upon either party "hanging up" before expiry of 25 the full time allowance.

IV. *Subscriber's station apparatus and operation.*

IV^a. The selector setter a^3 of each subscriber's station is preferably a rotatably adjustable dial 12 carrying, for adjustment or setting, a contact 13. A complementary selector-carried contact 13' will connect with 13 after movement of selector shaft 14, that 40 carries it through a number of steps corresponding with the setting of the contact 13. The selector shaft 14 is normally held in one position by the action of a suitable return spring 15, and is movable by a ratchet wheel 16 driven by a suitable pawl 17 carried by the armature 18 of the selector magnet 19 which is generally similar to an alternating-ringer magnet and which is constantly bridged across the line as by wires 20—21. 45 22 is a holding pawl for wheel 16. Pins 23—23' on the step-up wheel govern the phone control switch 24, said switch being connected to the switch hook h of the instrument set by wire 25 and to the line wire 10 by connections 26—27. Since the grounded bell 28 of the instrument set a' makes contact with the switch hook h when the hook is down, and the receiver connections r make connection from said switch 50 hook to the line wire 11 when the switch hook is raised, it will be apparent that, as far as the selector operation is concerned, it is only when switch 24 is closed by one of the pins 23—23' that a subscriber at a 55 called station may get into functional con-

nection with the line. It is my preference that at all stations the first of the pins, 23', on the selector wheel 16 shall occupy the same number-position so that by setting the selector setter a^3 for that number all the subscribers on the line may be called at once. The same thought may be carried forward by special construction of any number of the selectors to close their switches 24 at the same time as where there are several parties 70 on the line who are particularly subject to call in common. The second pin, 23, occupies a position corresponding with a respective station number so that when the pin 23 of the selector for any subscriber closes the switch 24, the switches 24 of all of the other subscribers are open and they are accordingly locked out from establishing connection of their instrument sets with the line. The instrument set of a calling subscriber is connected with the line through other means. 80

IV^b. A pin 29 on the shaft of the selector, when in normal position, occasions the closure of a switch 30 which I term the magneto-lock-out switch, the construction being 90 such that the first step forward of the selector shaft will cause the opening of this switch 30. The magneto-lock-out switch 30 is connected by wires 31 and 32, respectively, through the magnet 33 of the magneto-bridger relay, to back contacts 34 and 35 of a three-blade gang switch a^7 (which I term the magneto-bridger switch) these contacts normally receiving the blades 36 and 37 that are direct connected by wires 38 100 and 39 to the terminals of the magneto a^2 . When the magneto first is operated, bridger magnet 33 is energized. (See Fig. 1, heavy-line circuit). Its armature is a latch for switch a^7 . It unlatches; the blades of switch a^7 spring over to their front contacts, to remain there until the release takes place. The front contacts 34' and 35' of the two leaves 36—37 are respectively connected by wire 40, switch contacts 41, 42, and wire 43 110 with line 11 and by wires 44, 27 with line wire 10. This action, therefore, bridges the magneto across the line. The circuit is 10, 27, 44, 35', 37, 39, a^2 (magneto), 38, 36, 34', 40, 41, 42, 43, 11. (See Fig. 4). 115

IV^c. Now, manifestly, the magneto of the calling station will supply alternating current to all of the bridged selector magnets 19 to operate the selectors at all stations on the line, and it will be apparent that the first advance of each selector will open the magneto-lock-out switch 30 appurtenant thereto; (see Fig. 4) so that when once the magneto of any calling station has been bridged on the line the magnetics at all other stations on the line are automatically locked out and functionally disabled. As a matter of preference the step up wheel of the selector is made with a large number of fine teeth so that the ringer movement of oper- 125 130

ating magnet 19 may be rapid and so that it takes a number of vibrations of the magnet armature, say 6, to produce a predetermined advance corresponding with one step of the selector setter. This decreases the liability of the selectors to get out of step.

IV^a. Impelled by selector magnets 19, the step up wheel 16 at each station will rotate, and the extent of rotation is determined by the position of the selector-setter contact 13 at the calling station. When the selector-moved contact 13' comes into connection with the adjusted contact 13 of the selector setter, the pin 23 on the selector wheel of the desired station will be closing its switch 24 (Fig. 4).

IV^b. At this point the operation of the selectors ceases, so as to hold the switch 24 at the station of the called subscriber closed and the magneto circuit connections at the calling station are changed so as to connect the magneto in a ground circuit including the ringers at the calling and called station. The calling subscriber continues to operate the magneto until his bell ceases to ring, its cessation showing that the called subscriber has answered the call. Such shifting of the magneto connection is automatically accomplished by the operation of a magneto-grounding-relay having a magnet 45, the armature of which normally latches the spring 41 of magneto-shifter switch a^8 back against its back contacts 42 and 42''. As soon as selectively set switch 13-13' at the transmitting station closes, it establishes a circuit for this relay magnet 45, from the magneto a^2 through wires 39, 46, switch 47, of the gang a^7 (now closed), wire 48, selectively-set switch 13-13', rotary connections 49, wire 50, magnet 45, wire 51 to back contact 42'' for blade 41 of switch a^8 , wire 40, switch 34'-36 and wire 38 to the magneto. (See dotted lines Fig. 4). Immediately upon establishment of this connection the magnet 45 attracts its armature unlatching switch blade 41 which springs forward, breaking the circuit just described at 41'-42'' and making connection with a front contact 42' which is connected by wire 52 with the switch-hook of instrument set a' and consequently with grounded bell 28. (See heavy lines Fig. 5).

IV^c. Now it will be seen a ringing circuit is established from ground at the transmitting station, bell 28, switch-hook, h , connections 52, 42', 41, 40, 34', 36, 38, magneto a^2 , 39, 37, 35', 44, 27, 10 to the called station and, at the called station, from line 10 by connections 27, 26 and the now closed selector-switch 24 by wire 25, switch hook and bell 28 to ground. Thus the two bells at the calling and called stations on the line, connected in series with the magneto at the calling station, are simultaneously rung.

65 When the party at the called station an-

swers, the bells, of course, cease to ring, as the last mentioned circuit is broken at the switch hook h of the called station.

IVe. Of course when the called subscriber takes his receiver from the hook he bridges his receiver across the line by connections from line 11, receiver r , hook h , 25, switch 24, 26, 27, line 10. At the calling station the instrument set is correspondingly bridged when the receiver is lifted from the hook, although through different connections. It will be understood that the magneto at each station is of the usual type short circuiting its own armature through a switch a^{20} when not in manual rotation, and so it will be apparent that at the calling station the receiver is bridged by connections 11, receiver r , switch hook, 52, 42', 41, 40, 34', 36, 38, a^{20} , frame of the magneto, 39, 37, 35', 47, 27, 10. (See Fig. 6).

IV^h. Regarding the inter-communicating functions, enabling any party on a line to call any other party thereon without attention from the central station, it will be apparent that the parts thus far described enable all of the functions of selection, calling and vocal communication to be effected. The releasing operation, however, involves the operation of certain central station apparatus, as an expedient for economical avoidance of requiring a comparatively powerful source of direct current supply at each transmitting station. But at the subscriber's station of course there is releasing mechanism for response to such central energy.

IVⁱ. The release means a^6 is diagrammatically shown as comprising a solenoid release magnet 55 adapted to be bridged across the line wires by connections 20, 20', and 21, 21' whenever a switch 56 of the polarized selector magnet 19 is closed. As far as its own functions are concerned it might be permanently bridged, but switch 56 enables the solenoid to be kept off the line except during its functional operation, and for a very brief interval during each selector-armature vibration. However the duration of the magneto impulses is not sufficient to work the relatively slow-acting release magnet 55, which is responsive only to direct current. When direct current of proper polarity is transmitted through the line, however, polarized magnet 19 responds to close switch 56 as long as the current is maintained on the line, and the release magnet 55 responds to such direct current fully to attract its spring-retracted core and thereby, through any suitable mechanical connections as schematically indicated in the drawings, to trip out the pawls for the selector wheel 16 and to force the spring sets switches a^7 and a^8 back to normal position where they may be latched by the spring retracted armatures of their respective magnets 33.

and 45. (See Fig. 7). The mechanical details of such releasing devices form no part of my present invention, and it will be understood that, (as is true with respect to 5 substantially all of the mechanical parts employed for convenient practice of my invention,) I have illustrated the mechanical connections only in such skeletonized form as suberves diagrammatic clearness, rather 10 than mechanical efficiency.

V. Central station call-responsive-device.

V^a. At the central station, it will be understood, the selector apparatus a^* has a 15 step up wheel 16^e which controls a switch 24^e to close said switch when the central number is called, the selector being actuated by a magnet 19^e and provided with a direct-current responsive release-magnet 55^e 20 corresponding in arrangement with the similar parts at each subscriber's station. It will be apparent, however, that the selector devices at the central station appurtenant to each line may be reduced to a 25 minimum, consisting simply of the selector magnet, wheel, switch and releasing magnet, for the obvious reason that the calling apparatus at the central station will be separate from the signal responsive selector and will be connected with the cord 30 circuit. At central station the switch 24^e might, of course, govern a connection with a grounded ringer like that at any other station, but preferably in lieu of such signal 35 receiving apparatus I arrange the switch 24^e to control the switch-board line lamp, l , so that the latter may operate after the usual fashion of the line lamp of any central switch-board. The particulars in 40 this regard will be later described.

VI. Central automatic control of party-line intercommunication.

VI^a. I have heretofore indicated that the 45 clearing out or releasing operation, at the subscribers' stations, resulting from energization of release solenoids 55 , is effected by direct-current power supplied from the central station. It is my preference that 50 such release be effected automatically, if either of two defined conditions shall exist, and also that the power arbitrarily to effect or to suspend such releasing operations at will be vested in the central operator. The 55 two conditions under which the release operation should preferably take place automatically are: First, if, after the expiration of a limited time (say one minute for example) allowed for ground-circuit ringing, the line wire 10 be grounded, as it is when either party "hangs up," or when the called party has not answered; and, second, upon the expiry of a further predetermined 60 period (say five minutes) to which the duration of a single call is limited by the rules 65

of the line, this regardless of the fact that the parties have not hung up.

VII. Central automatic devices—timer.

VII^a. The timer b^1 referred to in paragraph III^b is preferably a retarded train, set in motion whenever the line is energized for use, and operating to manipulate, mechanically, certain switches b^6 and b^7 at predetermined moments in its timed cycle. 70 60 is a wheel, retarded in rotation as by a suitable escapement 61 , adapted to be driven in rotation by the pawl 62 of an arm 63 which is subject to spring elevation for movement in the wheel-driving direction 80 and to potentiation by the action of a timer magnet, preferably in the form of a solenoid 64 , the action of which opposes the spring 65. The switch members that are controlled by the timer-lever 63 are, for convenient 85 diagrammatic illustration, divided into two groups b^6 and b^7 . The double throw switch b^6 , (which I will term the timer-magnet control-switch) has a spring leaf 66 that moves between back and front contacts 67 90 and 68 according as a spring-resisted switch-snapper or "flopper" 69 is "flopped" at opposite ends of the throw of timer arm 63 . The upper switch group, b^7 , which I will term the release-control switch, comprises a plurality of members all of which have their effective circuit connections opened when the timer arm 63 is moved to potentiated position, and which are acted on by the timer arm to close their respective 100 circuits in predetermined succession during the timed return-travel of the timer arm 63 . This upper switch group b^7 includes a ground switch 71 grounded by wire 72 , and a double throw switch comprising a 105 blade 73 linked to the timer arm 63 to move therewith. When the timer arm moves down, a pin 74 on the switch blade 73 opens ground switch 71 and holds it open until the timer arm 63 returns a distance proportioned to the allotted ringing time (see 110 Fig. 5). This is to make the releasing devices ground-responsive as hereafter more fully described. When nearing the end of its return it closes briefly (of or a few seconds in practice) a connection with contact 75 over which it wipes. (This is to give a warning signal on the line.) And last, on the rising movement of arm 63 occupying say 5 minutes, said blade 73 closes with 120 contact 76 . (See Fig. 7) This is for automatic clearing of the line upon lapse of the time circuit allowed by rule. Considering, mechanically the order of operation of these switch devices b^6 and b^7 it is evident 125 that when arm 63 is moved in a potentiating direction, or downward, blade 76 may follow blade 73 downward a short distance, while switch 66 — 67 is maintained closed until the potentiating movement is substan- 130

tially complete, then the "flopover" 69 is shifted and switch blade 66 is suddenly thrown down from contact 67 to contact 68. Beyond this the order of opening of the 5 upper switches is of no importance. Their order of closure has been mentioned, but it is not until after release switch 73—76 has firmly closed that the flop-over 69 is snapped back to normal position. It will be appreciated that this form of switch shown is selected for diagrammatic simplicity rather than mechanical expediency.

VIII. Central station release means.

15 VIII^a. The release means b^2 comprises a release magnet 80; mechanical restoring devices for the timer parts, and circuit controlling switch means for the battery b^3 , by which the latter may be bridged on the line 20 for a brief interval pending self-restoration of the release means and battery switch to normal.

VIII^b. The release magnet 80 of the timer controls a releasing lever 81 and when energized it potentiates said lever by pulling it over in opposition to a spring 82. Such potentiating movement throws the upper end of lever 81 to the right and its return movement, under the influence of its spring, 30 is itself retarded briefly, as for a few seconds, preferably by the same retarding train 60 which serves the timer arm. The potentiating movement of the release lever 81 throws out the pawl 62 for the timer arm 63 35 wherever said arm may be, engages a pawl 84 of the arm 81 with wheel 60, and also works a switch-snapper or "flopover" 86, thereby automatically to control a switch set b^9 for the battery b^3 as well as the latching 40 devices for certain other switches. The conditions thus established by the release-lever potentiating will maintain until the retarded return of the release lever to normal is completed, when flopover 86 will be thrown 45 back to normal, leaving all parts in normal position.

IX. Central station: Potentiating the timer.

IX^a. It will be observed that at central 50 there is normally bridged across the line the magnet 90 of a magneto-current-responsive relay. (See Fig. 2). This has connection by wires 91, the magnet coil, normally closed cut-out switch 92, wire 93, normally 55 closed cut-out switch 94, with wire 95, connected to line 11. The cut out switch 92 is one of a gang, b^{10} , of two switches normally latched in position, with switch 92 closed and the companion switch 96 open, by the 60 action of the relay armature. Consequently, as soon as a magneto current is transmitted over the line at the commencement of the selective signaling operation, magnet 90 is energized by current flowing through the

path 10, 91, 90, 92, 93, 94, 95, 11, whereupon 65 magnet 90 attracts its armature, unlatching switch b^{10} so that its blades spring over opening cut out switch 92 and closing switch 96. The switch 94 heretofore mentioned is one of a gang of three switches, the others 70 being double throw battery switches, and all controlled, for movement from normal position, by the flopover 86. The normal position of the double throw battery switches is with their central springs 97 and 97' 75 engaging their back contacts 98—98' which are connected to circuits local to the central exchange. The front contacts 99 and 99', respectively, of these battery switches b^9 are connected by wires 95' and 91' to wires 80 95 and 91, leading to the line wires 11 and 10, so that movement of the battery switches from normal position over to their front contacts will bridge the battery on the line. (See Fig. 7.)

IX^b. As soon as the magneto responsive relay 90 works, as heretofore described, in response to the first magneto impulses transmitted over the two line wires, the closure of switch 96 establishes a battery circuit 90 through the timer magnet 64 which is to potentiate the timer. (See Fig. 4). The circuit may be traced as follows: battery b^3 , switch 97—98, battery wires 100, 101, switch 96, connection 103, timer magnet 64, 95 connection 104, contact 67 to switch blade 66 of timer-magnet switch b^6 , connection 105, to junction 106 with battery wire 107 leading back to contact 98', blade 97' and battery. Accordingly the battery current, 100 flowing through the solenoid 64, energizes it, so that it pulls down the timer arm 63 potentiating the timer, and at the extreme limit of throw of the timer arm the "flop-over" 69 is worked, breaking at 66—67 the 105 circuit just described for the timer magnet and connecting the battery wire 107 with the lower contact 61, which is connected with the main switch blade 73 of the release-control switch b^7 by wire 109. Also this 110 potentiating movement of the timer arm opens the ground switch 71 and release switch 73—76, the successive closure of which is the prime function of the timer.

IX^c. Thus, almost immediately upon 115 commencement of the operation of the magneto at the calling station the timer at central station is potentiated. Generally, the arm 63 is started on its return movement before the selection of the called subscriber is 120 completed; and in any event the return movement of the timer arm 63 is going on during the interval when the calling subscriber is ringing the bell of the called subscriber. A predetermined time, say one 125 minute, elapses before the timer arm 63 is moved back far enough so that the insulated pin 74 on switch blade 73 has left the switch

leaf 71 and allowed the latter to close. After that 4 more minutes elapses, say, before release switch 73-76 closes.

5 *X. Central station: Release-controlling means.*

The automatic release and clearing out should take place before the full time allotment for a single call has expired in either 10 of two events: if the called party has not answered within the allotted ringing time; or if either party hangs up between expiry of the ringing time and expiry of the full call-limit of, say, 5 minutes. These results I 15 accomplish by the employment of a ground-responsive relay 111, having its magnet 111 in a battery-circuit controlled by the ground switch 71 and through its armature, in turn, controlling local circuits for the release mag- 20 net 80. The ground responsive magnet 111 is preferably of high resistance and is bridged across the line by wires 112-112' leading respectively to line wires 10 and 11, and it has a central tap 113 running to a 25 junction point 114 with a wire 115 leading from battery wire 100 direct to the release magnet 80. (See dotted lines Fig. 5.) Now it will be apparent that, at any time after ground switch 71 is closed, if there is a 30 ground on line wire 10, a ground-return, battery-energized circuit will be established via said ground on the line, wire 10, 112, half of coil 111, 113 to 114, up on 115, 100, 98, 97, battery b^3 , 97', 98', 107 to 106, 105, 35 71', ground switch 71, 72, ground. There- 40 upon the ground-responsive magnet 111 is energized, attracts its armature 120 to connect with front contact 121, and thereby closes a release circuit for release magnet 80, as hereafter described (paragraph XI^a). Half of the winding of the coil 111 is ample for the necessary energization. The only object in splitting the coil with the tap 113 is to prevent possible unbalancing of the line 45 by the establishment of the ground connec- 50 tions through switch 71, it being appreciated that such connection is maintained from the time of its establishment until the completion of the call.

XI. Releasing operation.

XI^a. The closure of the switch 120, 121 should result in energization of the release solenoid 80 for performance of its functional 55 operation; and the same effect should follow either from the closure of switch 73-76 at the end of the full allotted time for a call, or from a manual switch operation effected at will by the central operator. To secure 60 the desired results of release-control from these multiple points the release magnet 80 should have parallel circuit connections through the several control switches to battery b^3 . To this end the release magnet 80,

one terminal of which is connected by wires 65 115, 100, and switch 98-97 directly with the battery, as heretofore described, has its opposite terminal connected by wire 125 with a normally closed switch 126 appurtenant to an operator's release control key, 70 $c'-h$, and from the wire 125 (when connected with battery b^3) three alternative connections may be made back to the opposite battery wire 107, so that by closing any one of these three connections the battery circuit 75 for the releasing magnet may be established.

XI^b. One said connection may be made through a switch 128 appurtenant to the key ck and serving to connect the line wire 125 with wire 129 leading to a junction 130 with 80 the wire 107. Manifestly this gives the central operator a release-control circuit, b^3 , 115, release magnet 80, 125, 128, 129, 130, 107, b^3 that is independent of any automatic switch means.

XI^c. A second connection may be made from wire 125 through switch 126 to a wire 131 having a tap 132 to the front contact 121 of the ground responsive relay. The armature 120 of the ground responsive relay is 90 connected by wire 133 with the junction point 106 of the battery wire 107. Thus whenever relay 120 is attracted (if switch 126 be closed, as normally it is) the release circuit b^3 , 115, 80, 125, 126, 131, 132, 121, 95 120, 133, 106, 107, b^3 is established.

XI^d. The third connection is closable by timed release switch 73-76, blade 76 of which has connection 135 to wire 131. Its release magnet circuit is b^3 , 115, 80, 125, 126, 100 131, 135, 76, 73, 109, 68, 66, 105, 106, 107, b^3 . (See Fig. 6).

XIe. It will be observed that of the three parallel connections from wire 105 to battery 87, the two connections that may automatically be established, namely, the connection 120-121 controlled by the ground responsive relay and the switch connection 73-76 controlled by the timer, are both effected through the operator's manual switch 126 110 in series therewith; but that the third connection controlled by the operator, at switch 128, is direct. The result of this arrangement will be manifest. By manipulating key ck to open switch 126 energization of 115 the release magnet through either of the automatic agencies is prevented, and the line will not automatically be cleared, however great the lapse of time, until switch 126 is closed. On the other hand, regardless of 120 the position of either of the two automatic switching devices, a circuit for the release magnet may be closed at any time by switch 128, thereby peremptorily to clear the line.

XII. The line clearing operation.

XII^a. Assuming that an intercommunicating call has been made on the line and that

two stations have been in telephonic communication for the period of time occupied by the full rising movement of the potentiated timer arm 63, the automatic release operation that occurs when switch 73-76 is closed, just before the flopover 69 is thrown back to normal position, is as follows: Closure of switch 73-76 establishes a battery circuit local to the central exchange, including the battery b^3 and release solenoid 80, as described in paragraph XI^a. The direct current energizes the release magnet which shifts the release lever 81, throwing the pawl 62 for the timer arm out of engagement with the ratchet and allowing the timer arm to make the very last portion of its rising movement rapidly, to throw the flopover 69 to restored position, opening the switch 66-68 and thereby breaking the release magnet circuit. Also this movement of the release lever 81 shifts the flopover 86, throwing its upper portion to the left so that through suitable mechanical connections, as the levers 150, 151, it trips the latch for the armature of magnet 90, restoring the double pole switch b^{10} to initial condition, and at the same time it shifts the triple pole switch b^9 associated with the battery, so as to bridge the battery on the line. It will be observed that the shifting of the triple pole switch opens the switch 94 so that the magneto-responsive relay 90 is left disconnected with the line (pending return of the flop-over 86) and is not responsive to the battery current on the line. The shift of the switch blade 97-97' of switch b^9 brings the battery into connection with the wires 95' and 91' which, through wires 95 and 91, respectively, are connected to the line wires 10 and 11. The direct current thus supplied to the line affects the polarized magnets 19 of all of the subscribers' stations, and the corresponding magnet 19^c at the central station, the polarity of the current causing the normally raised ends of the relay magnets to descend so as to close the switch 56 in each instance. Accordingly direct current flows through each release magnet 55 and 55^c, bridged across the line by the closure of switches 56, so that the release magnets 55 or 55^c at each affected station performs its releasing function so that all selector and relay apparatus at each subscriber station is restored to normal in a manner heretofore described. This release action is shown in Fig. 7.

XII^b. In order to insure maintenance of the direct current in the line for a sufficient time to insure functioning of the release magnets 55, I prefer that the return movement of the central station releasing lever 81 to normal position after the breaking of the circuit for release magnet 80 at the switch 66-68, shall be retarded and, as dia-

grammatically illustrated, this may be done by causing a pawl 84 on said release lever to engage the retarded ratchet wheel 60, or any other suitable retarding device, so that some seconds must elapse between the shifting of the flopover 86 to bridge the battery on the line, and the return movement of said flop-over that restores the battery to its normal connection.

XII^c. It will be understood that the clearing out operations are exactly the same when a circuit for the release magnet 80 at central station is established either through the operation of the ground responsive relay b^{11} or the closing of switch 128 of the operator's control key *ck*.

XIII. Warning signal preceding timed release.

I have pointed out that just before the release switch 73-76 closes, the switch blade 73 makes a brief contact with a switch point 75. This is in order to give a warning signal to the parties on the line indicating that their allotted time for communication is almost expired. As a specific means to give this signal I provide a buzzer 160 connected with one winding of a repeating coil 161, the other coil of which is bridged across the line, and I arrange said buzzer for energization from a small local battery 162 whenever the switch 73-75 is closed. The circuit is established from battery 162 by wire 163 to switch 75-73, returning via 109, 68-66 (closed under these conditions) 105, 106, 164, 165, buzzer 160, coil 161 to battery 162. As a result a slight buzzing sound is made on the line for a short period of time at a predetermined interval before the closure of switch 73-76 that controls the automatic line-clearing operation.

XIV. Calling through central-line lamp operation.

XIV^a. The operations heretofore described have been predicated upon the assumption of inter-communicating calls between subscribers on the same line. The calling operation to get the attention of central is the same as the operation to call any other party on the line, the central station being indicated by a number on the selector setter, like any other station. When the central selector *a*^{*} is stepped up in response to the central call, to close the switch 24^c, a circuit is established for the line lamp *l* from the central battery b^3 as follows (see dot-and-dash lines, Fig. 4): from battery b^3 , switch 97'-98', wires 107, 106, 164, 170, selector switch 24^c, wire 171, normally closed switch contacts 172-173, (connected with a spring of jack *j* to open when a plug *p* is inserted) wire 174, lamp *l*, wire 175, back to battery wire 115, through switch 98-97, to the other terminal

of battery b^3 . The line lamp glows until the plug p is inserted in the usual jack j , the spreading of the jack spring mechanically shifting the spring leaf 173 into connection 5 with its front contact, 176, breaking the aforesaid lamp circuit at 172-173. This front contact 176 for spring 173 is connected by wire 177, switch 178 and wire 179 back to wire 170, thereby throwing a parallel 10 connection around the open switch 172-173, but the switch 178 is closed by a pin 180 on the selector wheel a^* only when the latter is in normal or cleared-out position. This parallel connection is afforded to insure that the 15 line lamp will glow (as a clearing out signal) when either party hangs up and the clearing-out operation is effected, for (incidentally to the clearing out operation,) the selector at central station thereby has its 20 wheel returned to normal position, closing switch 178 and reestablishing the circuit for lamp l through the shunt connection 173-176, 177, 178, 179 around the open jack-controlled switch 172-173. When the operator withdraws her plug the clearing out 25 signal is extinguished, for switch 176-173 is opened.

XIV^b. When the automatic clearing of the line has been made impossible by the operator's throwing key ck to the right to open release-disabling switch 126 (as for instance in the event of a toll call where no time limit is imposed) the central selector a^* is not cleared or restored to give the clearing out 35 signal through switch 178. Therefore the line lamp l should be made to respond, under these conditions, to the energization of ground responsive relay b^{11} . To this end I provide a switch 185, closed by key ck when 40 switch 126 is opened. Switch 185 is included in wires 187, 188 running from lamp wire 174 to a front contact 189 for armature 120 of the ground responsive relay b^{11} .

When line 10 is grounded by a subscriber 45 hanging up, the magnet 111 is connected from wire 10 to ground via 10, 111, 113, 114, 115, 98-97, battery b^3 , 97'-98', 107, 105, 71', 71, 72, ground. Its armature 120 then closes the lamp circuit battery b^3 , 97-98, 100, 115, 50 175, l , 174, 187, 185, 188, 189, 120, 133, 106, 107, 98'-97', battery b^3 . This causes the lamp l to glow to acquaint the operator with the fact that she may restore her key ck and so clear the line.

55 *XV. The cord circuit.*

XV^a. The operator's cord circuit apparatus D must, of course, comprise cords d arranged for connection with the calling selector a^d which may be substantially of the same type as the calling apparatus at the subscribers' stations. Various arrangements, and a greater or less degree of refinement in automaticity of action may be provided, but

in the present instance I have diagrammatically shown merely a simple form of cord arrangement for purposes of disclosure. Referring to Fig. 3 the cord d has its answering and calling sections d^1 and d^2 , (that are respectively connected with the answering 65 and calling plugs, p^a and p^c), associated with each other through a repeating coil d^3 . An operator's instrument set d^4 is associated with the cord in any suitable fashion and the selective calling apparatus is associated with 70 the calling plug section d^2 . Of course, as is well understood in the art, since the interchange of electrical energization between the two cord sections occurs only through the repeating coils, "compromise" cords may be 75 used to effect connection of a subscriber with a line of some other system, requiring any special form of cord equipment, in which event one section of the cord will take the arrangement appropriate to the different or 80 "outside" system.

XV^b. The calling section d^2 of the cord is connectible with the selective call apparatus through a key K. In lieu of the magneto generator a constantly operating source 90 of alternating current supply as generator d^1 may be employed, connectible in bridged relation to the line and to the step-up magnet of the selector a^d when the key K is thrown to the left, closing switches K' and K^2 and opening switch K^3 that leads to the repeating coil. The selector a^d receiving alternating current, steps up until its setting switch d^9 closes circuit d^{11} that includes battery d^{12} , switch d^{13} and magnet d^{10} , whereupon the magnet d^{10} , properly energized, attracts its armature (which is thereupon latched in attracted position by an armature of the releasing magnet d^{22}) opening switch d^{13} and also a switch d^{14} 105 that is interposed in the connection between the generator d^1 and switch K^2 . This leaves the generator, one terminal of which is grounded, connected only with the sleeve strand of the cord, (which connects with 110 line wire 11) and the step-up action of the selectors stops. When the operator then throws key K to the right she moves switch K^4 that closes a connection for the tip-strand of the cord through a lamp d^{15} , the generator d^1 to ground, thereby to ring the bell of the selected station, and that also opens the cord-strand leading back to the repeating coil. To restore the selector to normal the operator closes key d^{20} which 115 is connected in a circuit d^{21} with battery d^{12} and magnet d^{22} and said magnet, when energized, unlatches switches d^{13} and d^{14} and also withdraws the pawls of the selector a^d to permit its spring-restoration to 120 125 initial position.

XV^c. Manifestly a single selector apparatus may be multiple-connected to any de-

sired number of cords, as the operator can make only one selective call at a time in any event, the construction shown permitting her to call on a second line while still ringing the called party on a first-called line.

XVI. Résumé of operation.

The calling party sets his selector setter a^3 to indicate the number of central, if he is going to call to some other line, or the number of the desired party on his own line, if the call is to be intercommunicating. Assume the latter condition and that the set call is for station No. 9: By continually turning his magneto the caller secures the line, operates all selectors thereon, locking out the magnetos at all of the stations that there may be no interference with his call; stops the selector operation when all the selectors on the line have stepped forward 9 steps, and rings the bells at his own and at the called station, conditioning his own instrument set and that at the called station for communicating connection with the line. The operation of the calling magneto a^2 first energizes relay 33 (Fig. 1) which switches (at a^7) the magneto into bridged relation to the line (Fig. 4) so that the bridged selector magnets 19 of all stations on the line respond, stepping up the selectors a^4 synchronously until, at the calling station, the settable switch connection 13—13' is made between the selector moved contact and the selector-setter contact (dotted lines, Fig. 4); whereupon magneto grounding relay magnet 45 is energized, tripping its switch a^8 to break its own circuit and to connect the calling magneto from line 10 to the grounded bell at the calling station. Accordingly all of the selectors stop; selector at station 9 standing in such position that its control switch 24 is closed, connecting the switch hook of the called station to line 10 and establishing the ringing circuits. (Fig. 5.) Removal of the receivers from the switch hooks bridges the two instrument sets on the line, (Fig. 6) that at the called station through the switch 24 and at the calling station through contact 42'' and the short circuiting switch a^{20} of the magneto that is closed whenever the magneto is not in rotation. At central station the first magneto impulses on the line energize the normally bridged relay 90 (Fig. 1), the switches, b^{10} , of which are unlatched, opening the relay circuits and closing a circuit from the central battery b^3 to the timer potentiating magnet 64 through the switch 96. (Fig. 4.) The timer is spring returned against retardation of its train. After a definite time lapse, during which all of the switches of the releasing set b^7 are open, (such interval being allowed for the ringing operation to secure response of the called party,) the timer arm lifts

lever 73 far enough to permit closure of the ground switch 71 which connects the ground responsive relay b^{11} to the line 10 (dotted lines, Fig. 5); later, almost at the limit of its return movement, the timer arm causes closure of the switch 73-75 for the buzzer 160 so that through the repeating coil 161 a slight noise may be made on the line to warn the parties that their time has nearly elapsed; and then almost at the conclusion of its range of throw, after the lapse of the total time allowed for a single conversation by the rules of the line, said timer arm closes the release switch 73-76, (Fig. 6) and then, last of all, it works flop-over 69 to shift switch b^6 . (Fig. 7.)

The release switch 73-76 is in parallel with a switch 120-132 controlled by the magnet 111 of ground responsive relay b^{11} — and these two switches are in series with a release-disabling switch 126 manually controlled by the central operator's key ck . The circuit on which these three switches operate connects the battery and the releasing solenoid 80, so that if either the ground-relay controlled switch (120-132) or the release switch (73-75) be closed the release solenoid is energized from central battery. Therefore, either if the party hangs up during the time allowed for conversation (in which case he will ground the line 10 and cause the ground responsive relay b^{11} to operate) or when the switch 73-76 closes by lapse of the maximum time, the release is automatically effected, but the central operator by opening switch 126 may disable these automatic switches, or by closing switch 128 may establish a battery-to-release-solenoid circuit independently of these automatic switches. Energization of the release solenoid in any event moves the release lever 81, (Fig. 7) the return movement of which is retarded for a short interval of time, to give ample time allowance for the clearing out operation. The solenoid impelled movements of the release lever, 81 causes the gang switch b^9 appurtenant to the central battery to be shifted to bridge the battery on the line. This causes all of the selector magnets 19 at the respective signaling stations to throw their armatures down in such direction as to close their switches 56 which bridge the releasing magnets at the subscriber's station on the line and these releasing magnets (which are not adapted to respond to the alternating magneto current) respond to the direct current to actuate the mechanical releasing devices for the several selectors, clearing the line and restoring all subscriber's apparatus to normal condition. When the central station releasing lever 81 effects its spring return to normal condition it causes the battery bridging switch b^9 to snap back to normal position and the restoration of all auto- 130

matically moved parts at the central station to normal has been completed.

When the central station is called the selector a^* closes at 24° the line lamp circuit 5 that receives its current from the central battery. (Dot-and-dash lines, Fig. 4.) When the operator plugs in the line lamp circuit is broken at the plug controlled switch 172. When the call has been completed and the automatic clearing out takes place the return of the central station selector a^* to normal condition closes the circuit for the line lamp through switch 178, and this circuit is broken at 176 when the operator removes her plug. When the operator throws switch 126 to disable the automatic line-clearing means, by moving her controlling key ck , the same key movement closes at switch 185 a connection for front contact 10 189 of said relay b^{11} that makes the response of the ground relay, occasioned by a subscriber hanging up, to energize the line lamp 7 and give a clearing-out signal.

The operator's calling device is connectable to any one of her cord circuits, and, save that for convenience a constant source of alternating current may be substituted for a hand magneto, with suitable changes of details, the central's calling arrangement 25 is practically the same as that of any other subscriber. Throwing key K for any cord to the left connects the selector magnet with the calling section d^2 of that cord. Throwing said key K to the right connects 30 grounded generator d^7 , to the tip-strand of the cord (connectible with line wire 10 through the jack) and rings the called subscriber. Closure of key d^{20} releases the selector which may be used to make other calls 35 while the first-called party is being rung.

The system which I have heretofore described as a single embodiment of my invention, is illustrated as having the talking circuits energized by local batteries, as is common practice in many party-line exchanges; but where it is desired to use central energy 45 for the talking circuits, in lieu of local batteries at the subscribers' stations, this may readily be accomplished with but few 50 changes in the organization of the system. Under such circumstances I prefer that the central talking battery be connected with the line only pursuant to the selecting operation, or subsequent to an allotted time adequate for the performance of the selecting 55 function. This in order to prevent the battery from receiving alternating current impulses, as it would if bridged on the line during the interval when the magneto is 60 bridged for its selector-actuating function. It will have been noted that the common battery that occasions the release operation is connected with the line to establish a definite polarity, to accomplish the releasing 65 function. Therefore on the other hand,

where central energization for talking purposes is provided, the battery connections for supply of talking current should produce the opposite polarity on the line, where the selector-magnets are, as in the present 70 illustration, bridged across the line-wires.

In Fig. 8 I have outlined a central energy system embodying my invention, all circuits and apparatus being the same as those heretofore described, except for the few 75 changes now to be noted.

In the drawings, for simplicity of illustration I have shown the talking battery tb as a battery independent of the release battery b^2 , although consolidation of all of the 80 central station means of direct-current-supply into one source might be effected. The talking battery tb is capable of being bridged on the line by the simultaneous closure of two switches 190 and 191 in series 85 connection therewith, one switch, 191, being timed, as to effective closure, to insure that the battery-bridging will be subsequent to the selecting operation. Since the system shown provides a central station timer, that 90 instrumentality may conveniently be employed for timing the closure of switch 191. In the specific arrangement shown switch 190 is associated with the "flop-over", 69, to be closed at the end of the down stroke or 95 potentiating pull of the timer-arm, when flop-over 69 is thrown down. The other switch 191 is arranged for closure on the return movement of the timer arm after a lapse of time, (which may be empirically 100 determined) equal to or slightly in excess of the maximum time that is required for selection of the highest number on the line.

At each subscriber's station the telephone set a^* is of course appropriately changed in 105 wiring to meet the central energy conditions, one known form of instrument wiring being shown.

It will be observed that when the system 110 in general is operated as heretofore has been described, pursuant to signal initiation from any subscriber's station, the talking battery tb will remain open-circuited during the down stroke of the timer arm, as switch 191 will open before switch 190 closes, and that 115 then, after switch 190 is closed owing to the shifting of the "flop-over", 69, the circuit will continue open for the predetermined maximum-selecting-time, until switch 190 is closed by the rising arm of the timer. This 120 will bridge the talking battery tb on the line, there to remain until the timer arm reaches its highest position and throws the flop-over back to normal position, so reopening switch 190. In order that calls 125 which are not to be subject to maximum-talking-time-limit (such as long distance calls) may not be subject to interruption by the cutting off of battery when the timer arm is restored to highest position, I pref- 130

erably provide in connection with the key *ck* a switch 192, in multiple with the two series switches 190, 191, and is closable by the throwing of key *ck* to the right; that is, 5 to position preventing the automatic release, and clearing out. Of course when switch 192 is thus closed, the talking battery *tb* will be maintained on the line until the operator manually restores key *ck*.

10 Save for the modification incident to installation of my system on a basis of either central or local battery energization of the talking circuit, to meet the two basic conditions most commonly met in practice, I 15 have shown herein only a single embodiment of my invention for purposes of disclosure. It will be understood however, that in its broader aspects my invention is not limited in detail to the structure and arrangement 20 specifically shown but is susceptible of many modifications within the spirit of my invention and the scope of the appended claims.

I believe it to be broadly new with me to employ full magneto-generated-alternating 25 current for intercommunicating-and-central-calling selection in one circuit and ringing in another circuit; to employ in connection with such selective system, a distinctive-current release; and also in employing as a 30 release-relay the same alternating-current-responsive magnet that actuates the step up selector. And I believe it to be broadly new to time automatically the maximum allotment for ringing and for talking service; 35 and, in a system employing alternating current selecting current on the line, to time automatically the connection of a central-talking-battery to the line. These and other features I intend to claim broadly for their 40 individual benefits and combinatively in their advantageous associations herein disclosed.

I claim:—

1. In a selective telephone signaling system, the combination with a metallic line, 45 of subscribers' instrument sets, each including a grounded bell, and at each subscriber's station a source of alternating current supply, a step-up selector responsive to alternating current adapted on a predetermined step to connect the instrument set with the line, and settable means coöperating with the selector to control the number of steps duration of current flow to the line from the 50 source of alternating current supply at said station.

2. In a selective telephone signaling system, the combination of a metallic line; at 55 each subscriber's station an instrument set including a grounded bell; a source of alternating current supply, a step-up selector responsive to alternating current adapted, after a predetermined number of steps, electrically to connect said instrument set and bell to the line, a selector setter comprising

a switch settable to close at a predetermined position of the selector, means for bridging the source of alternating current supply on the line wires, and means controlled by said switch of the selector setter for automatically interrupting the bridging connection and grounding the bell side of the line through said source of current supply to ring the grounded bell at the selected station. 70

3. In a selective telephone signaling system, 75 the combination of two line wires; at each subscriber's station an instrument set including a grounded bell; an alternating current generator; a selector responsive to alternating current in the line and adapted, 80 on a certain step, to condition the bell for ground connection on one side of the line and the telephone instrument for bridging connection with the line; a selector-bridging relay having its magnet normally connected 85 with the source of current supply and acting when energized to bridge the source of current supply on the line, thereby to actuate all selectors; selector setting means including a switch settable to close after any 90 predetermined number of selector steps; a circuit local to said station, and means therein responsive to alternating current from said source of supply, and controlled by said settable switch, to operate on switch-closure, 95 for disconnecting said source of current supply from one side of the line and grounding it for operation of the bell at the called station.

4. In a selective telephone signaling system, 100 the combination of two line wires; at each subscriber's station an instrument set including a grounded bell; an alternating current generator; a selector responsive to alternating current in the line and adapted, 105 on a certain step, to condition the bell for ground connection on one side of the line and the telephone instrument for bridging connection with the line; a selector bridging relay having its magnet normally connected 110 with the source of current supply and acting when energized to bridge the source of current supply on the line, thereby to actuate all selectors; a selector controlled switch for breaking said normal connection, a circuit local to said station, and means therein responsive to alternating current from said source of supply, and controlled by said settable switch to operate on switch-closure, 115 for disconnecting said source of current supply from one side of the line and grounding it 120 for operation of the bell at the called station.

5. In a selective signaling system the combination with two line wires, of subscribers' apparatus at each station comprising an instrument set having a grounded bell, a switch hook for connection with one line wire and telephone instruments connected with the other side of the line; a magneto generator; a step-up selector responsive to 125

5 magneto current in the line; a bridger relay; a selector controlled switch normally connecting said bridger relay with said magneto; a selector-controlled switch for connecting the switch hook to its side of the line after a predetermined number of steps; a selector setter comprising a switch adjustable for closure after predetermined number of steps of the selector; and a magneto-
10 grounding relay having its magnet controlled by said switch of the selector setter, the switch means of said relay adapted to break the bridge connection of the magneto with the line and connect a side of the line
15 with the local switch hook.

6. In a selective telephone signaling system, the combination with the line wires instrument sets and their bells, of subscribers' apparatus comprising at each station 20 a source of alternating current supply, an alternating-current responsive selector arranged to close a circuit for the bell at a predetermined step, and means, in local circuits of each station, responsive to the 25 home source of alternating current supply automatically to bridge the source of current supply on the line and to connect it in circuit with the bell after a predetermined operation of the home selector.

7. In a selective telephone signaling system, the combination with a line, a selector, alternating-current responsive operating means therefor, direct-current-responsive releasing means therefor, a source of alternating current supply; and means of direct current supply for the releasing means.

8. In a selective telephone signaling system, the combination with a line, of subscribers' station apparatus comprising a 40 source of alternating current supply, a selector, a settable selector controlled means for connecting said source of alternating current with the line to produce predetermined selector-operation, and direct-current responsive release means; and central station apparatus comprising a source of direct current supply, and means, automatically responsive to line conditions initiated at the subscriber's station, for connecting 45 said direct current source with the line to energize the subscriber's release means.

9. In a selective telephone signaling system, the combination of the line; subscribers' station apparatus comprising a switch hook, a selector, alternating current responsive means for actuating said selector, a selector release means responsive to direct current, means of alternating current supply, and settable means for determining connection of said source of alternating current supply with the selector-actuating means; and at the central station a source of direct current supply and means, for connecting 55 the same with the line to actuate the releasing means, automatically responsive to

switch-hook operation of any connected subscriber.

10. In a selective telephone signaling system, the combination of the line; subscribers' station apparatus comprising a switch hook, 70 a selector, alternating current responsive means for actuating said selector, a selector release means responsive to direct current, means of alternating current supply, and settable means for determining connection 75 of said source of alternating current supply with the selector-actuating means; and at the central station a source of direct current supply and automatic means for connecting the same to the line upon occurrence of predetermined conditions upon the line to energize the releasing means at the subscribers' stations.

11. In a selective telephone signaling system, a line, subscribers' station selective 85 means associated with the line to select and connect the instrument sets of the calling and called subscribers, electro-responsive release means for said selective means, and automatically timed means for automatically energizing said release means.

12. In a selective telephone signaling system, a line, subscribers' station selective 95 means associated with the line to select and connect the instrument sets of the calling and called subscribers, electro-responsive release means for said selective means, and automatically timed means for automatically energizing said release means after lapse of a predetermined maximum time, and for 100 transmitting a warning signal on the line prior to such releasing energization.

13. In a selective telephone signaling system, the combination with the line, of subscribers' station signaling apparatus productive of and responsive to alternating currents, and releasing means responsive to direct current; central station means comprising a battery, a timer potentiated in response to alternating current in the line, 110 timer release means, means operated by said timer release means for bridging the battery on the line, and control means for said timer release means controlled by the timer.

14. In a selective telephone signaling 115 system, the combination with the line, of subscribers' station signaling apparatus productive of and responsive to alternating currents and releasing means responsive to direct current; central station means comprising a battery, a timer potentiated in response to alternating current in the line, timer release means, means operated by said timer release means for bridging the battery on the line, and manually operable means 120 for disabling said control means.

15. In a selective telephone signaling system, the combination with the line, of subscribers' station signaling apparatus productive of and responsive to alternating cur- 130

rents and releasing means responsive to direct current; central station means comprising a battery, a timer potentiated in response to alternating current in the line, 5 timer release means, means operated by said timer release means for bridging the battery on the line, control means for said timer release means including a ground responsive magnet, and means controlled by the timer 10 for connecting said ground responsive magnet between the line and ground.

16. In a selective telephone signaling system, the combination with the line, of subscribers' station signaling apparatus productive of and responsive to alternating currents and releasing means responsive to direct current; central station means comprising a battery, a timer potentiated in response to alternating current in the line, 15 timer release means, means operated by said timer release means for bridging the battery on the line, control means for said timer release means including a ground responsive magnet, and means controlled by the timer 20 for connecting said ground responsive magnet and the battery between the line and ground.

17. In a system of the character described, the combination with a line, of subscribers' 30 station apparatus comprising call transmitting and receiving means, a source of current supply therefor, and releasing means responsive to releasing current of a character different from the calling current, of a central station source of supply of releasing current, and timing means, potentiated in response to the calling current, for supplying releasing current to the line after a lapse of predetermined intervals.

40 18. In a system of the character described, the combination with a line, of subscribers' station apparatus comprising call transmitting and receiving means, a source of current supply therefor, and releasing means responsive to releasing current of a character different from the calling current, of a central station source of supply of releasing current, and timing means, potentiated in response to the calling current, for supplying releasing current to the line upon an occurrence of the ground on the line after the lapse of a predetermined interval.

45 19. In a system of the character described, the combination with a line, of subscribers' station apparatus comprising call transmitting and receiving means, a source of current supply therefor, and releasing means responsive to releasing current of a character different from the calling current, of a central station source of supply of releasing current, timing means, potentiated in response to the calling current, for supplying releasing current to the line after a lapse of predetermined intervals, and central station 55 means for transmitting a warning sig-

nal on the line just before the lapse of said predetermined time.

20. In a system of the character described, the combination with a line, of subscribers' station apparatus comprising call transmitting and receiving means, a source of current supply therefor, and releasing means responsive to releasing current of a character different from the calling current, of a central station source of supply of releasing current, timing means, potentiated in response to the calling current, for supplying releasing current to the line after a lapse of predetermined intervals, means controlled by said timer for conditioning said source of release current supply for connection with the line after lapse of a predetermined time, and manually operable switch means for the operator for occasioning or suspending at will such connection of said releasing current source of supply with respect to the line.

21. In a selective signaling system, the combination of a line; subscribers' station apparatus comprising a source of current supply of one character, selector apparatus responsive to current of that character, release means responsive to line-transmitted current of a different character; and, at a central station, means for the supply of the release current, and a timer governing the association of the release current supply means with the line.

22. In a selective signaling system, the combination of a line; subscribers' station apparatus comprising a source of current supply of one character, selector apparatus responsive to current of that character, release means responsive to line-transmitted current of a different character; and, at a central station, means for the supply of the release current, and a timer potentiated in response to selector-actuating current and governing the association of the release current supply means with the line.

23. In a selective telephone signaling system, the combination of a metallic line; subscribers' station apparatus each comprising a source of supply of current of one character, bridged selector apparatus responsive to current of that character, release means responsive to current of a different character and a switch-hook having selector-controlled connections for grounding the line; and, at a central station, a timer, means to potentiate said timer in response to selector-operating current, a source of release-current supply, means to connect said source in relation to the line to energize the release means at the subscribers' stations, and timer-controlled means responsive to the grounding operation of any connected switch hook, after lapse of a timer-determined interval, and controlling the last-foresaid means.

24. In a selective telephone signaling system, the combination of a metallic line; sub-

- scribers' station apparatus each comprising a source of supply of current of one character, bridged selector apparatus responsive to current of that character, release means 5 responsive to current of a different character arranged to bridge the line and a switch-hook having selector-controlled connections for grounding the line; and, at a central station, a timer, means to potentiate said timer in response to selector-operating current, a source of release-current supply, means to connect said source in bridged relation to the line to energize the release means at the subscribers' stations, and timer-controlled 10 means responsive to the grounding operation of any connected switch hook, after lapse of a timer-determined interval, and controlling the last-aforesaid means.
25. In a selective telephone signaling system, the combination of a metallic line; subscribers' station apparatus each comprising a source of supply of current of one character, bridged selector apparatus responsive to current of that character, release means 20 responsive to current of a different character and a switch-hook having selector-controlled connections for grounding the line; and, at a central station, a timer, means to potentiate said timer in response to selector-operating current, a source of release-current supply, means to connect said source in relation to the line to energize the release means at the subscribers' stations, and timer-controlled means in circuit with said source 30 of release current supply responsive to the grounding operation of any connected switch hook, after lapse of a timer-determined interval, and controlling the last-aforesaid means.
40. 26. In a selective telephone signaling system, the combination of a two-wire line, subscriber's station apparatus each comprising a source of alternating current supply, bridged selector apparatus responsive to alternating current, and direct-current-responsive 45 release means connected with the line and, at a central station, a timer, means to potentiate said timer in response to alternating current, a source of direct current supply, means to connect said source with the line to actuate the subscriber's release means, and to release the timer, said means including a direct-current responsive magnet, a normally-open circuit for said magnet including the source of direct current, and a plurality of release-initiating switches controlling said circuit and respectively timer-controlled and manually-controlled. 50
55. 27. In a selective telephone signaling system, the combination of a two-wire line, subscriber's station apparatus each comprising a source of alternating current supply, bridged selector apparatus responsive to alternating current, and direct-current-respon- 60
- sive release means connected with the line and, at a central station, a timer, means to potentiate said timer in response to alternating current, a source of direct current supply, means to connect said source with the line to actuate the subscriber's release means, and to release the timer, said means including a direct-current responsive magnet, a normally-open circuit for said magnet including the source of direct current, and a plurality of switches controlling said circuit, one thereof being manually controllable at the central station and another being timer controlled. 70
75. 28. In a selective telephone signaling system, the combination of a two-wire line, subscriber's station apparatus each comprising a source of alternating current supply, bridged selector apparatus responsive to alternating current, and direct-current-responsive release means connected with the line and, at a central station, a timer, means to potentiate said timer in response to alternating current, a source of direct current supply, means to connect said source with the line to actuate the subscriber's release means, and to release the timer, said means including a direct-current responsive magnet, a normally-open circuit for said magnet including the source of direct current, and a timer controlled switch controlling said circuit, and a manual cut-out switch for disabling said timer-controlled switch. 80
85. 29. In a selective telephone signaling system, the combination of a two-wire line, subscriber's station apparatus each comprising a source of alternating current supply, bridged selector apparatus responsive to alternating current, direct-current-responsive release means connected with the line and a switch-hook having selector-controlled connection for grounding the line; and, at a central station, a timer, means to potentiate said timer in response to alternating current, a source of direct current supply, means to connect said source with the line to actuate the subscriber's release means, and to release the timer, said means including a direct-current responsive magnet, a normally-open circuit for said magnet including the source of direct current, timer controller means responsive to grounding of any connected switch hook to close said circuit, and timer controlled means for closing said circuit after lapse of a maximum time. 90
95. 30. In a selective telephone system, the combination of a line, at each subscriber's station, a source of alternating current supply, a selector, a selector setter, a grounded bell, and means automatically responsive to 100 operation of said source of alternating current supply to bridge said source on the line to actuate the several selectors, and means controlled by the selector setter automatically to interrupt said bridge connec- 110

- 120
- 125
- 130

tions and connect the generator with the grounded bell when the selector is in predetermined position, and direct current responsive release means, of central station apparatus comprising a source of direct current supply, a timer, automatic means responsive to alternating current on the line to potentiate said timer, and means, timed in operation by said timer, automatically to 10 connect the direct current battery with the line to energize the station releasing means.

31. In a selective telephone system, the combination of a line, at each subscriber's station a source of alternating current supply, a selector, a selector setter, a grounded bell, and means automatically responsive to operation of said source of alternating current supply to bridge said source on the line to actuate the several selectors, and means 15 controlled by the selector setter automatically to interrupt said bridge connections and connect the generator with the grounded bell when the selector is in predetermined position, and direct current responsive release means, of central station apparatus comprising a source of direct current supply, a timer, automatic means responsive to alternating current on the line to potentiate said timer, a ground responsive relay, means 20 controlled by the timer for connecting said ground responsive relay magnet between the line and ground for actuation upon grounding of the line, and means controlled by said ground responsive relay for connecting said 25 source of current supply with the line to release the selective apparatus at the subscriber's station.

32. In a system of the character described, the combination with a two wire line, of subscriber's station apparatus, comprising alternating current supply means, selector means responsive to alternating current of predetermined selective duration to actuate said selector to connect the subscriber's instrument set with the line, and settable means 40 coöperating with said selector to determine the selector actuating duration of the operation of said alternating current supply means, and direct current responsive release means associated with the line, of central station apparatus comprising a source of direct current supply normally disconnected from the line, means, including an automatic timer, automatically to connect said source 45 of direct current supply with the line, and manually operable means for suspending the operation of the last aforesaid means.

33. In a selective telephone signaling system, a line, instrument sets, subscriber's station selecting means associated with the line to select and connect the instrument sets of the calling and called subscriber, electro-responsive release means; at a central station, a source of release-current supply, means to 55 connect the same with the line to release the 60

selectors for restoration, a signal responsive selector, a line lamp normally controlled thereby, a plug-opened switch arranged to disable said normal controlling means, and switch connections closable on restoration 70 of the central selector to bridge said plug-opened switch.

34. In a selective telephone signaling system, the combination of a line, instrument sets, subscriber's station selecting means associated with the line to select and connect the instrument sets of the calling and called subscribers, electroresponsive release means; and at a central station means to supply direct current of one polarity to the line to 80 energize the instrument sets, and direct current of the opposite polarity to the line to actuate the release means.

35. In a selective telephone signaling system, a line, instrument sets, subscriber's station selecting means associated with the line to select and connect the instrument sets of the calling and called subscribers; electroresponsive release means, at a central station means to supply direct talking 90 current to the line after a selector-operating interval; and means to supply direct current of opposite polarity to the line to operate the release means.

36. In a selective telephone signaling system, a line, instrument sets, subscriber's station alternating current-responsive selecting means on the line to select and connect the instrument sets of the calling and called subscribers, means of alternating current 100 supply therefor; and at a central station, means for supplying direct current to the line to energize the instrument sets for talking subsequently to the selective operation.

37. In a selective telephone signaling system, a line, instrument sets adapted for central-battery energization, at each subscriber's station a source of alternating current supply and alternating-current responsive selecting means on the line to connect the instrument sets of the calling and called subscriber; and at a central station, a timer, a talking-current battery, and means controlled by the timer to connect said battery on the line subsequently to the selecting operation.

38. In a selective telephone signaling system, a line, instrument sets adapted for central-battery energization, at each subscriber's station a source of alternating current supply, alternating current-responsive selecting means on the line, and direct current responsive release means on the line, and at the central station a timer, potentiated by the selecting operation and means 120 controlled by the timer for supplying direct current of one polarity to the line for talking and direct current of opposite polarity for release.

39. An intercommunicating, party line,

telephone system comprising a line, at each subscriber's station an instrument set, a ringer, a ringing magneto, and alternating-current-responsive selecting means, and 5 means, at each subscriber's station for effecting connection through one circuit of the magneto with all of alternating-current-responsive selecting means, and connection through another circuit with the ringer of 10 the selected station.

40. An intercommunicating party-line telephone system comprising a line, at each subscriber's station a magneto, and selecting means including an alternating-current-responsive magnet bridged on the line, and selector release means governed by said magnet, and at central station a source of direct-current supply to energize said magnet to effect selector-release.

20 41. In a lock-out telephone system, subscriber's instrument sets, means to connect them in energized relation, means to lock out the sets of all other subscriber's means to release said lock out means, and timing 25 means automatically potentiated incidentally to establishment of the energized connection and controlling the releasing means to effect release of the lock out means after a predetermined time.

30 42. In a telephone system, subscriber's instrument sets common to a party line, means to connect any set to the line and lock out the others, means to release the lock out means, and timing means, connectible with 35 the line for controlling the releasing means to occasion release of the lockout means after a predetermined time.

43. In a lockout party-line telephone system, the combination of a line, subscriber's 40 instrument sets, respective selectors for connecting a selected set with the line, means to lock out the sets of non-selected stations, means to release said lock-out means, and automatic timing means controlling the 45 releasing means to effect lock-out-release after a predetermined time.

44. In a lockout party-line telephone system, the combination of a line, subscriber's instrument sets, respective selectors responsive 50 to alternating current for connecting a selected set with the line, means to lock out the sets of non-selected stations, direct-current responsive means to release said lock-out means, means for supplying to the line 55 alternating current to actuate said selectors, means of direct current supply, and automatic timing means controlling the connection of said direct current supply means with the line for actuating said releasing 60 means to effect lock-out-release after a predetermined time.

45. In a selective telephone signaling system, a line, subscriber's station instrument

sets and selective means associated with the line to connect the instrument sets respectively therewith, electro-responsive release means for said selective means, and automatically timed means for automatically energizing the release means.

46. In a telephone system, a party line 70 having at each station an instrument set and a selector for controlling its connection with the line, said selectors having predetermined normal position and being responsive to alternating current; in combination with 75 means for supplying alternating current to the line, means to be set for predetermined the selector which shall act in response to said current, and means, automatically operable in response to a predetermined condition of necessary occurrence, for restoring the selectors to normal position.

47. In a telephone system, a party line having at each station an instrument set, means selectively responsive to alternating 85 current for connecting any selected instrument set with the line and locking out non-selected sets, and selector release means responsive to current of different character; in combination with means for supplying 90 alternating current to the line; means to be set for predetermined the selector which shall act in response to said alternating current; and means for supplying the different releasing current to the line.

48. In a telephone system, a party line having at each station an instrument set, step up means each having a normal position, and responsive to a plurality of alternating-current impulses to take each step, 100 and acting on a predetermined step to connect the instrument set with the line, in combination with a source of alternating current supply, means to be set for predetermined the step on which a correspondingly-set step-up means shall act, and means, automatically operable in response to a predetermined condition of necessary occurrence, for restoring the selectors to normal 105 position.

49. A telephone system comprising a line, selecting means at a subscriber's station including an alternating-current-responsive magnet bridged on the line and selector release means governed by said magnet, means 115 for supplying alternating current to said magnet to effect selector setting and means for supplying current of different character to said magnet to effect selector-release.

In testimony whereof I hereunto set my 120 hand in the presence of two subscribing witnesses.

FRANK W. ADSIT.

In the presence of—

GEO. T. MAY, Jr.,
MARY F. ALLEN.
